NOVELTY ROTARY DISPLAY STAND

Byron Haase, Bloomington, Ind.

Application May 4, 1946, Serial No. 667,323

6 Claims. (Cl. 40—126)

1

This invention relates to improvements in novelty rotary display stands.

An object of the invention is to provide an improved novelty rotary display stand for placing in store display windows to attract the attention of persons walking by the windows to cause them to stop and inspect the store display in said windows.

Another object of the invention is to provide an improved novelty rotary display stand for placing in store display windows, said stand including a surface simulating streets and a number of small structures simulating houses or stores with open doors, together with a number of steel ball containing capsules placed at random on the streets, and a plurality of rotatably supported permanent magnets positioned immediately below said surface operated by a display motor for attracting the steel ball containing capsules for moving them into and out of said buildings.

A further object of the invention is to provide an improved novelty rotary display stand for positioning in store display windows whereby a plurality of colored capsules containing steel balls will move about the surface of said stand by concealed magnets rotatably supported and operated by an electrically operated display motor, said display stand being attractive and interesting to watch, and relatively inexpensive to manufacture and produce.

Other objects will appear as the description proceeds.

In the accompanying drawings which form a part of this application,

Figure 1 is a perspective view of the improved novelty rotary display stand;

Figure 2 is a vertical sectional view taken through the improved novelty rotary display stand;

Figure 3 is a view taken on the line 3—3 of Figure 2;

Figure 4 is a perspective view of one of the rotary permanent magnet supporting disks shown in upside down position, and

Figure 5 is a detail sectional view showing a steel ball containing capsule on the display head or surface, with a permanent magnet directly under said surface.

Like characters of reference are used throughout the following specification and the accompanying drawings to designate corresponding parts.

In carrying out the invention, there is provided an improved novelty rotary display stand including a substantially rectangular shaped housing generally denoted by the reference numeral 1, and comprising a supporting bottom 2 with four cooperating vertically extending side walls 3, 4, 5 and 6 adapted to seat on the pe-

2

ripheral flange 7 formed about the lower sides of said bottom 2, and secured to said bottom in any desired manner. An attractive covering 8 of any desired material may be placed about the four sides of said housing 1, while bracing triangular shaped blocks 9 will be placed in the four corners of the housing 1 to reinforce and strengthen the same. Also, a plurality of bracing strips 10 will be positioned in spaced relation to extend across each of said sides 3, 4, 5 and 6, and will be suitably secured thereto.

A head member or surface 11 formed of a thin skin or parchment like material will be positioned across the upper end of the housing 1 and secured tightly there across in any desired manner, as for example like the head of a drum.

A suitable coating or covering 12 will be placed over portions of the upper surface of the head member 11 to simulate lawns or grass, while the intervening uncoated areas will extend at random to simulate streets 13. A plurality of structures 14 simulating buildings having open doorways 15 will be disposed at various locations at the street ends, and advertising signs 16 will be placed over the buildings and in different positions about the lawns 12 and also as a background for said display device. All of the streets 13 will more or less radiate outwardly from a central zone, and any desired number of capsules 17 containing steel balls 18 will be placed about the display on the several simulated streets.

The operating mechanism for the display device will now be described. An electric display motor generally designated by the reference numeral 19 will be secured centrally on the bottom 2 in any desired manner and will be connected by the electric conductor 20 to any suitable source of electric current supply (not shown). The motor 19 will be provided with a vertically extending rotatable shaft 21, and will support the large main rotating disk 22 which is reinforced by the spider 23.

A pair of bearing supporting studs 24 and 25 extend upwardly through the disk 22 and above the same at oppositely disposed points. Said studs having securing flanges 26 and 27 formed on their lower ends, and screws 28 will extend through said flanges and into the disk 22.

Bearing collars 29 and 30 will extend about the bearing supporting studs 24 and 25, and will extend through the small rotatable disks 31 and 32, being attached thereto by the screws 32 and arranged in spaced relation from the upper surface of the main disk 22. Ball bearings 34 and 35 will be seated in bearing apertures in the metal bearing retaining disks 36 and 37 and will be supported on the upper ends of the bearing supporting studs 24 and 25, said disks being held in spaced relation from the upper surface of the

ball rotatable disks 31 and 32 by means of the screws 38.

Radially extending baffle strips 39 will be secured to the lower surfaces of the small rotatable disks 31 and 32 to be engaged by the upwardly extending pegs 40 supported in spaced relation to outline a circle, and secured to the bottom 2 in any desired manner.

Oppositely disposed permanent magnets 41 and 42 are supported on the upper surfaces of the small disks 31 and 32.

A pair of radially extending opposed arms 43 and 44 are secured to the upper surface of the main or large disk 22 by means of the screws 45, and support the permanent magnet 46 on their outer ends, and the spring retarding fingers 47 on their inner ends adapted to engage the peripheries of the small disks 31 and 32 to prevent reverse rotation of the same.

As seen from the drawings, the permanent magnets are positioned immediately below the surface 11 so that when the large disk 22 is rotated by the motor 19, the smaller disk supporting the magnets 41 and 42 will also be rotated and the baffle strips 39 will be engaged by the upwardly extending pegs 40, while the spring retarding fingers 47 prevent reverse movement of said disk. As the magnets move about under the surface 11, the colored capsules 17 with the enclosed steel balls 18 will be moved by magnetism to travel up and down the simulated streets and into and out of the various house structures, thereby effectively attracting the attention of persons passing by the store window in which the unique display is positioned.

The number of pegs 40 used in the mechanism will be variable and may be placed in different positions to produce different patterns of movement of the magnets, which could be adapted to a racing course or roller rink, or any other desired attraction which might be set over the mechanism.

From the foregoing description, it will be apparent that a highly effective and interesting novelty rotary display stand will have been provided.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

1. In a novelty rotary display stand including a housing having a bottom and interconnected side walls, a head surface member forming the top for said housing, a display on said surface member simulating streets leading to open doored building structures, a plurality of capsules containing metal balls disposed on said surface member, a rotatably mounted disk in said housing, means for driving said disk, a plurality of smaller disks rotatably mounted upon said first mentioned disk, means rigidly mounted on said bottom to engage and cause rotation of said smaller disks and permanent magnets supported by said smaller disks directly below said surface member for attracting said metal balls in said capsules for moving them over said surface mem-

ber and into and out of said building structures.

2. In a novelty rotary display stand including a housing having a bottom and interconnected side walls, a head surface member forming the top for said housing, a display on said surface member simulating streets leading to open doored building structures, a plurality of colored capsules containing metal balls disposed on said surface member, a disk rotatably mounted in said housing, means for rotating said disk, bearing studs supported in opposed position on said disk, smaller disks rotatably mounted upon said bearing studs, means rigidly mounted on said bottom to engage and cause rotation of said smaller disks and permanent magnets supported on said smaller disks for attracting said metal balls in said capsules for moving them over said surface member and into and out of the building structures.

3. In a novelty rotary display stand including a housing having a bottom and interconnected side walls, a head surface member forming the top for said housing, a display on said surface member simulating streets leading to open doored building structures, a plurality of colored capsules containing metal balls disposed on said surface member, a disk rotatably mounted in said housing, electric motor for driving said disk, spaced oppositely disposed bearing studs mounted through said disk, bearing elements on the upper ends of said studs, smaller disks positioned about said bearing elements, means rigidly mounted on said bottom to engage and cause rotation of said smaller disks, permanent magnets supported in opposed position on the upper surfaces of said smaller disks, and a ball bearing suspension for said smaller disk adapted to support the same in spaced relation from said first mentioned disk.

4. The subject matter as claimed in claim 3, radially disposed slats on the lower surface of said smaller disks for engaging said means for varying the speed of rotation of said disks.

5. The subject matter as claimed in claim 3, a plurality of radially disposed slats on the under surface of said smaller disks, said means comprising annularly arranged pegs secured to said bottom for engagement with said slats for engagement therewith for varying the rotation of said smaller disks, and means for preventing a reversed direction of motion of said smaller disks.

6. The subject matter as claimed in claim 3, slats formed on the lower surfaces of said smaller disks, means for engaging said slats for varying the speed of rotation of said disks, oppositely disposed arms supported by said large disk, permanent magnets supported at the outer end of said arms, and means on the inner ends of said arms for preventing a reverse direction rotation of said smaller disks.

BYRON HAASE.
